UNITED STATES PATENT OFFICE.

WILLIAM DIETER, OF BROOKLYN, NEW YORK, ASSIGNOR TO E. W. BLISS COMPANY, OF BROOKLYN, NEW YORK, A CORPORATION OF WEST VIRGINIA.

REDUCING-VALVE FOR AUTOMOBILE-TORPEDOES.

1,211,104.

Specification of Letters Patent. Patented Jan. 2, 1917.

Application filed September 20, 1916. Serial No. 121,148.

To all whom it may concern:

Be it known that I, WILLIAM DIETER, a citizen of the United States of America, residing in the borough of Brooklyn, county 5 of Kings, city and State of New York, have invented certain new and useful Improvements in Reducing-Valves for Automobile-Torpedoes, of which the following is a specification.

10 This invention relates to automobile torpedoes in which the air pressure from the compressed air reservoir or flask is reduced first through an initial pressure-reducing valve and then by a secondary or final pressure-reducing valve to bring it to the required pressure at which it is delivered to 15 the turbine or other engine for propelling the torpedo.

The object of the invention is to economize by preventing waste of compressed air and to guard against injury to the torpedo by preventing the possibility of an excessive pressure of air reaching vulnerable portions of the apparatus.

20 25 The preferred embodiment of the invention is shown in the accompanying drawings, wherein,—

Figure 1 is a fragmentary longitudinal vertical section of the torpedo, the parts being shown in a somewhat diagrammatic arrangement in order to illustrate their connections; Fig. 2 is a vertical transverse section of the torpedo showing the reducing valves and heater, and their respective connections.

30 35 The torpedo shown in Fig. 1 has in addition to the usual air flask or compressed air reservoir A, a fuel reservoir B designed to contain alcohol or other liquid fuel, and a water reservoir C. These are constructed 40 in a manner shown in United States Patents Nos. 1,022,486, dated April 9, 1912, and 1,125,979, dated January 26, 1915. The torpedo shown has primary and secondary pressure-reducing valves constructed generally 45 after the manner of those set forth in Patent No. 1,136,660, dated April 20, 1915. These patents may be referred to for a more complete illustration of certain features 50 herein shown, or which may be applicable in connection with the present invention.

Referring to Fig. 1, the compressed air from reservoir A passes through a duct *a* to a starting valve *D* of any usual or suitable construction, which normally closes the passage and opens it automatically upon the launching of the torpedo. Thence the air flows through a duct *b* to the primary pressure-reducing valve *E*, and thence through a duct *c* to the secondary pressure-reducing valve *F*. In the primary valve it is reduced from the air flask pressure (which at the outset may, for example, be in the neighborhood of 2800 pounds per square inch, and which during the run of the torpedo falls to a minimum of perhaps 700 or 800 pounds) to an intermediate pressure which may approximate, for example, 600 pounds. The secondary valve reduces the air pressure from this intermediate pressure to the pressure at which the air is fed to the turbine or engine, and which pressure varies according to the speed at which the torpedo is to be driven, which, as a working example, may be assumed to be 400 pounds per square inch. The air at this latter pressure passes through a duct *d* to the air heater or combustion chamber *G* (commonly called "superheater"), in which it is heated by the burning of alcohol or other liquid fuel there- 55 in, and its volume thereby increased. Commonly, also, water is sprayed into this heater which by the heat is converted into steam, which further increases the volume of the effluent mixture. From the heater the heated gaseous mixture passes out through a pipe *e* and is led to the engine or motor. In the construction shown in Fig. 2 the pipe *e* leads to the nozzle *f* of the turbine (H in Fig. 1), this being a well-known construction. 60 65 70 75 80 85 90

The alcohol or other fuel from reservoir B passes to the heater through a tube *g* leading to an injection nozzle *g'*. Likewise, water from the reservoir C passes through a tube *h* to an injection or spray nozzle *i* entering the heater. To prevent back flow through the pipes *g*, *h*, these are commonly fitted with check valves *j*, *j'* of suitable construction. The alcohol and water are caused to flow out through the pipes *g*, *h* by admitting compressed air to the upper portions of 95 100

the vessels B, C, this air being admitted under a reduced pressure somewhat higher than that at which the air enters the heater. In the example shown, air at reduced pressure is led from duct d through a tube k to a valve shell l , and thence through tubes k^1 and k^2 to the respective vessels. The valve shell l may contain valves of the construction set forth in Patent No. 1,022,486.

- 10 The pressure-reducing valves E and F may be of the construction shown in detail in Fig. 2. The valve E comprises a tappet or valve proper m on a stem n carrying a piston or plunger p for approximately balancing the valve; this plunger moves with a close working fit in the cylindrical portion q of the valve shell, and passes therethrough into the chamber r , in which there is a spring s which presses against the plunger and tends to open the valve. The pressure on the outlet side acting against the tappet m tends to close the valve, and the eduction pressure (in duct c) is determined by the stress of the spring s relatively to 25 the unbalanced area of the valve. The secondary valve F is of the same construction as the primary valve, except that its spring s' is made adjustable so as to vary the final pressure fed to the motor and 30 thereby determine the speed at which the torpedo should be driven. For this purpose it has the usual adjusting screw t and means for determining the precise adjustment to be given.
- 35 So far as described the construction is old and well-known. The nature of the present invention will now be set forth.

In order to make the working parts of the valves E, F move freely, so that these valves 40 shall operate with the desired degree of accuracy, it is necessary to provide an amount of clearance between the plunger p and its cylinder q which permits a certain leakage of air. In the secondary valve this leakage 45 is not serious, because the difference between the induction and eduction pressures is moderate (in the example given being only 200 pounds); but with the primary valve, where the difference between the induction and 50 eduction pressures is much higher (being commonly above 2000 pounds per square inch, the loss of air through leakage around the plunger amounts to a considerable waste of energy. The air loss through this leakage 55 has been found to commonly exceed five per cent. of the total weight of air stored in the air flask.

To avoid this waste is the primary object of the present invention. To this end the 60 spring chamber r , instead of being left open or vented to the interior of the torpedo as heretofore, is closed. If no vent were given from this chamber the leakage would quickly build up a pressure in this cham-

ber, which would have the effect of opening the tappet m wider and thereby permitting a higher intermediate pressure to pass to the secondary valve, a result which would largely defeat the advantage of using two successive pressure-reducing valves, and 70 which, also, would be liable to have a disastrous effect upon other parts of the apparatus. To avoid these results the air which enters the closed chamber r is conducted through a tube u and caused to enter 75 the heater G, where it is utilized along with the air coming from the secondary valve for driving the torpedo. As the pressure in the heater is approximately that which is fed to the engine (say 400 pounds in the example given), it results that approximately 80 this pressure is caused to exist in the chamber r . Consequently, this pressure acting upon the exposed area of the plunger p is added to the pressure of the spring s , tending to open the primary valve. This would cause the air passing the primary valve to be delivered at a correspondingly higher intermediate pressure; and to avoid this result the spring s is made much weaker than heretofore, so that the combined pressure of the spring and the back pressure of air in the chamber r is the same in its effect upon the primary valve as the pressure of the spring 90 alone in such valves as heretofore constructed. It results from this that the air leaking from the primary valve is utilized, while the operation of the primary valve remains under normal conditions precisely the same as heretofore.

It is of the utmost importance that the primary reducing valve should function normally so as to choke down the pressure from that in the air flask to approximately the uniform pressure at which the air is fed to the secondary valve. The air, either at this intermediate pressure or at the final pressure to which it is reduced by the secondary valve (and slightly above the pressure in the heater) is conducted through the tubes k , k^1 , k^2 to the alcohol and water reservoirs B and C. These reservoirs are necessarily of somewhat light construction and are unadapted to carry an air pressure much greater than that which is thus fed to them in normal operation. If through some derangement of the primary valve this pressure were to run much above the normal, it might result in bursting one or both of these vessels and thereby wrecking the torpedo. It is highly 115 important to avoid all risk of the happening of such an accident. Such deranged action of the primary valve might result from a fracture of the secondary valve, that is, the breaking of the valve stem connecting the 120 tappet with the plunger, so that the air would pass freely through the secondary valve. This would result in the air enter-

ing the heater at nearly the pressure existing in the intermediate duct *c*. This increased air pressure would be conducted to the motor and would have the effect of driving the 5 torpedo at a higher speed; this result would not be seriously objectionable, but another ensuing result might prove disastrous, namely, that the higher pressure in the heater, being conducted back through duct *u* to the chamber *r*, would add to the pressure tending to open the primary valve, and would have the result of opening this valve wider, so that the pressure of its discharge 10 would be increased. This increased pressure 15 being in turn fed to the heater, would result in a correspondingly increased pressure in the chamber *r*, and this in turn would open the inlet valve still wider, resulting in a still further increased outlet pressure; thus cumulatively 20 the inlet valve would be opened wider and wider until it was forced wide open and nearly the full flask pressure would be streaming out through the valve passages and heater. This cumulative effect would 25 occur so rapidly as to be practically instantaneous. The increased pressure might destroy the heater and wreck the turbine, but in any event it would shortly be communicated to the fuel and water vessels *B* and *C* and would burst one or both of these vessels and thereby wreck the torpedo.

To avoid these disadvantages is the object of the second part of the invention. According to this, provision is made for instantly 35 stopping any back flow of air from the heater toward the chamber *r*; and for permitting the escape from this chamber of any pressure materially in excess of the normal pressure therein. The first result is attained 40 by interposing a check valve in the duct *u*. The second result is attained by applying a safety valve or blow-off in communication with the chamber *r* adapted to discharge the pressure when it rises in said 45 chamber to an amount somewhat in excess of the normal (say, for example, 500 pounds as compared with the normal 400 pounds).

In the construction shown a ball check valve *v* is interposed in the passage *u* so that 50 in case of a back flow it will seat against a seat *w* and close the vessel. Normally it seats against the notched end of a plug *w'* so as to afford a free flow around the ball.

The safety valve is shown as a tappet *y* 55 closing a lateral port in the duct *u* (or otherwise communicating with the chamber *r*) and pressed to its seat by a spring *z* which reacts against a shoulder in the valve shell *v'* which incloses it. This spring is constructed 60 to have the required stress to hold the valve closed until the release pressure is attained. It results from this construction that in case of a breakage or other derangement of the secondary valve *F* so that the

resulting pressures are increased, the back flow toward the chamber *r* closes the check valve and stops this flow; thereupon, as the pressure in *r* builds up, due to leakage around the plunger, when this pressure reaches that at which the safety valve opens 70 the pressure thereupon escapes freely into the air space within the torpedo. If, for example, the safety valve is set to 500 pounds, the pressure discharged from the primary valve will rise a corresponding 75 amount above the normal (say 600 pounds), or, for example, to perhaps 800 pounds, but not farther.

The construction may be varied and equivalents substituted, and any necessary 80 changes to adapt the invention to other constructions of torpedoes may be made without departing from the invention.

What I claim is:—

1. In an automobile torpedo, the combination with a source of compressed air and a pressure-reducing valve, of means in connection with such valve for conducting leakage of air from the high pressure side of such valve to a point beyond the valve where this 90 leakage can be utilized.

2. In an automobile torpedo, the combination with primary and secondary pressure-reducing valves, of means in connection with the primary valve for conducting leakage 95 from the high pressure side thereof to a point beyond the secondary valve where such leakage can be utilized.

3. In an automatic torpedo, the combination with a source of compressed air and 100 primary and secondary pressure-reducing valves, and a heater beyond the secondary valve, of means for conducting leakage from the high pressure side of said primary valve to said heater.

4. In an automobile torpedo, the combination with a source of compressed air and a pressure-reducing valve comprising a balancing plunger, a spring, and a spring chamber, of means for conducting air leaking 110 into said chamber to a point beyond said valve where such leakage can be utilized, and means for preventing a back flow of pressure into said chamber.

5. In an automobile torpedo, the combination with a source of compressed air and a pressure-reducing valve comprising a balancing plunger, a spring, and a spring chamber, of means for conducting air leaking 115 into said chamber to a point beyond said valve where such leakage can be utilized, and a relief valve for discharging excess of pressure from said chamber.

6. In an automobile torpedo, the combination with a source of compressed air and a 125 pressure-reducing valve comprising a balancing plunger, a spring, and a spring chamber, of means for conducting air leak-

ing into said chamber to a point beyond said valve where such leakage can be utilized, means for preventing a back flow of pressure into said chamber, and a relief valve 5 for discharging excess of pressure from said chamber.

In witness whereof, I have hereunto

signed my name in the presence of two sub-scribing witnesses.

WILLIAM DIETER.
